UNITED STATES PATENT OFFICE.

CHARLES G. DUFFY, OF KANSAS CITY, MISSOURI.

FEED-WATER HEATER.

Application filed July 25, 1927. Serial No. 208,392.

My invention relates to improvements in feed water heaters adapted particularly for use in connection locomotive boilers.

One of the objects of my invention is to provide a novel feed water heater, with which the water fed to the boiler can be quickly heated to a high temperature by the exhaust and gaseous products of combustion.

10 A further object of my invention is the provision of a novel construction which enables of its being easily and quickly and thoroughly cleaned of dirt, sediment or scale.

15 My invention provides further novel baffling means for interrupting the course of travel of the gaseous products of combustion from the flues to the smoke stack.

The novel features of my invention are 20 hereinafter fully described and claimed.

In the accompanying drawings, which illustrate the preferred embodiment of my invention,

Fig. 1 is a central vertical sectional view 25 showing my improved feed water heater mounted in the smoke box of a locomotive.

Fig. 2 is a view of the same, partly in front elevation, partly in vertical section, and partly broken away.

30 Fig. 3 is a view of the same, partly in plan, partly in horizontal section, and partly broken away.

Fig. 4 is an enlarged section on the line 4-4 of Fig. 3.

35 Fig. 5 is an enlarged section on the line 5-5 of Fig. 3.

Similar reference characters designate similar parts in the different views.

1 designates the usual locomotive boiler 40 shell having therein the steam and water space 2, the smoke box 3, front tube sheet 4, flue tubes 5 discharging into the smoke box, the exhaust nozzle 6, petticoat pipe 7 and smoke stack 8.

45 In the smoke box 3 I provide a water heating and conducting means comprising, preferably, an inverted U shaped water heating receptacle 9, to the opposite arms of which, near the lower ends thereof, are respectively connected two water supply con-

ductors, 10, provided respectively with check valves 11', Fig. 3.

The transverse portion of the receptacle 9 is provided at its rear edge with a water outlet 11, Fig. 4. Said transverse portion is 55 also provided therethrough with a vertical opening 12, which aligns with the nozzle 6, and through which extends the petticoat pipe 7.

For draining the receptacle 9, the arms 60 thereof have respectively connected thereto adjacent to their lower ends two discharge pipes 13, each having a valve 14 adapted to be manually operated, said pipes being extended through the bottom of the boiler 65 shell 1, and the valves 14 being at the outer side of the shell.

The opposite sides of the arms and of the transverse portion of the U shaped receptacle 9 may be braced by connecting stay 70 bolts 15.

The receptacle 9 may be supported on a baffle plate 16, Fig. 1, which is disposed between the arms of the receptacle 9, at the lower ends thereof, and which extends rearwardly from the forward edges of said arms to the rear edges thereof, and thence upwardly to the transverse portion of the receptacle 9 and thence to the front tube sheet 4 to which the upper rear edge of the baffle 75 plate may be welded or otherwise secured. Stay braces 17 may also be fastened to the top of the transverse portion of the receptacle 9 and to the inner sides of the shell 1, Fig. 3. 80

To the front edge portion of the baffle plate 16 may be releasably secured by bolts 18 a forwardly inclined apron 19, Fig. 1.

Connecting the outlet 11, which may be a short piece of tubing welded into the receptacle 9, with the steam and water space 2, is a sinuous water conducting means, which, preferably, comprises the following described parts.

A series of water conducting chambers 95 20, 21, 22, 23, 24, 25, 26, 27, 28, 29, 30, 31 and 32 are connected in series alternately with a series of water conducting pipes 33, 34, 35, 36, 37, 38, 39, 40, 41, 42, 43 and 44, the first chamber 20 of the series being connected to 100

the outlet pipe 11 of the receptacle 9, and the first pipe of the series, 33 is connected at its upper end to the bottom of the first chamber 20, the lower forward end of the pipe 33 being connected to the rear side of the chamber 21, which is the first of a horizontal row comprising the chambers 21, 23, 25, 27, 29 and 31 disposed and fastened to the under side of the baffle plate 16.

10 The chamber 20 is one of an upper rear row comprising the chambers 20, 22, 24, 26, 28, 30 and 32.

15 The front end of the pipe 34 is connected to the rear side of the chamber 21 and its rear end is connected to the bottom of the chamber 22, to which is also connected the upper rear end of the pipe 35, the front end of which is connected to the rear of the chamber 23. The remainder of the pipes 20 are similarly connected to the remaining chambers, the last pipe 44 having its rear upper end connected to the bottom of the last chamber 32.

25 The last chamber 32 has connected to its rear side a T 45, Fig. 3, to which are connected two conductors 46 and 47 which connect with the space 2 of the boiler and which are respectively provided with check valves 48 and 49, which open toward the space 2.

30 The baffle plate 16 closes the space at and between the lower ends of the arms of the receptacle 9, and at the rear edges of said arms. Between said arms at the front edges thereof may be mounted a screen 50, Figs. 1 and 2, for arresting cinders.

35 The pipes 33 to 44 inclusive are disposed below and at the rear of the baffle plate 16, so that the heated gaseous products of combustion discharged from the flue tubes 5 strike said pipes, so as to heat the water therein.

40 The nozzle 6 extends through the baffle plate 16 and discharges between the arms of the receptacle 9, thus heating the water in said receptacle, which is also heated by the gaseous products passing upwardly and rearwardly over the apron 19.

45 The water entering the receptacle 9 through the conductors 10, will be heated and will pass through the outlet pipe 11 into the chamber 20, thence through the pipe 33 into the chamber 21, thence by the pipe 34 into the chamber 22, then by the pipe 35 into chamber 23, and so on through the remaining connected pipes and chambers until it reaches the last chamber 32 through the last pipe 44, from which last chamber it will pass by the T 45 into and through the conductors 46 and 47 into the steam and water space 2, at which time it will have become highly heated.

50 In order that the pipes 33 to 44 inclusive may be easily cleaned of sediment, scale or rust, the tops of the chambers 20, 22, 24, 26, 28, 30, and 32, and the fronts of the chambers 21, 23, 25, 27, 29, and 31 are provided

in their front sides with clean out openings 51, Figs. 4 and 5, which respectively align with the adjacent ends of the pipes connected with said chambers.

55 Respectively fitted in the holes 51 are removable screw plugs 52. By removing the adjacent plugs in the holes alining with the ends of the pipes, access may be had to the interior of each pipe through the ends thereof.

60 I do not limit my invention to the structure shown and described, as many modifications, within the scope of the appended claims, may be made without departing from the spirit of my invention.

65 What I claim is:—

1. In a feed water heater, the combination with a boiler shell having a smoke box and a steam and water space, and an exhaust nozzle in the smoke box, of an inverted U shaped water heating receptacle in said smoke box having an inlet for water and an outlet for water and having an opening through its transverse portion between its arms alined with said nozzle, water conducting means connecting said outlet with said steam and water space, and a plate closing the space between said arms at the lower ends and rear edges thereof, and forming with said U shaped receptacle a chamber of which said arms are the side walls of said chamber.

70 2. In a feed water heater, the combination with a boiler shell having a smoke box and a steam and water space, and an exhaust nozzle in said smoke box, of an inverted U shaped water heating receptacle in said smoke box having in its transverse portion between its arms an opening alined with said nozzle, a baffle plate through which said nozzle extends disposed between said arms, said plate extending between the lower ends and rear edges of said arms, and water conducting means connected with said outlet and with said steam and water space.

75 3. In a feed water heater, an inverted U shaped water heating receptacle having an inlet and an outlet for water, and having between its arms through its transverse portion an opening for conveying exhaust steam therethrough, a baffle plate disposed between the said arms at the lower ends and rear edges thereof, and conducting means connected with said outlet and adapted to be connected with the steam and water space of a boiler and having a sinuous portion below and at the rear of said baffle plate.

80 4. In a feed water heater, the combination with a boiler shell having a smoke box, an exhaust nozzle therein, and a steam and water space, of an inverted U shaped water heating receptacle having an inlet and an outlet for water, and having between its arms through its transverse portion an opening alining with said nozzle, a baffle plate

through which said nozzle extends disposed between said arms at the lower ends and rear edges thereof, water conducting chambers and pipes connected with each other in series in alternate order, the first of said chambers connecting with said outlet, said baffle plate being disposed between said re-

ceptacle and some of said pipes and chambers, and a water conductor connected with the last of said chambers and said steam and water space. 10

In testimony whereof I have signed my name to this specification.

CHARLES G. DUFFY.
